ENGINE STARTER DRIVE

Maurice P. Whitney, Elmira, N. Y., assignor to
 Eclipse Machine Company, Elmira, N. Y., a corporation of New York

Application January 27, 1937, Serial No. 122,580

3 Claims. (Cl. 74—7)

The present invention relates to engine starter drives and more particularly to an improved fastening arrangement for retaining the parts of the drive in assembled relation.

5 Engine starter drives as articles of commerce are usually in the form of a unit adapted to be mounted on the extended armature shaft of a starting motor, and incorporate means for so locating the drive thereon that when the starting 10 motor is mounted in its intended position, the drive pinion will be in proper position to engage and cooperate with a gear on a member such as the flywheel of the engine to be started. Thus in the form of starter drive disclosed in the patent 15 to Sekella 2,062,430, the elements of the drive are assembled on a sleeve which is located on a motor shaft by means of a pin and key.

It is an object of the present invention to provide a novel starter drive assembly which forms a unitary article of commerce especially 20 adapted for easy and rapid mounting and attachment to a motor shaft.

It is another object to provide such a device including novel means for locating and retaining the drive on the motor shaft.

25 It is a further object to provide such a device embodying special provisions for preventing the locating and retaining means from becoming dislodged by handling or vibration of the drive in shipment and distribution.

30 Further objects and advantages will be apparent from the following description taken in connection with the accompanying drawing in which:

35 Fig. 1 is a side elevation partly in section of a starter drive embodying the present invention; Fig. 2 is an end view from the left in Fig. 1; and

40 Fig. 3 is an enlarged sectional detail showing the parts as they are assembled in the drive for shipment.

45 Referring to the drawing, there is illustrated in Fig. 1 a barrel type drive of the type disclosed in the patent to Sekella cited including a sleeve 1 on which is slidably journaled a screw shaft 2 having a nut 3 threaded thereon. The nut 3 is rigidly connected by means of a barrel 4 to a pinion 5 which is adapted to slide freely on the extended armature shaft 6 of a starting motor and to be moved by said nut and barrel into and 50 out of engagement with a member, not illustrated, of an engine to be started.

55 The sleeve and screw shaft are yieldably connected by means of torsion and compression drive spring 7 anchored at one end to the screw shaft 2 by means of an anchor member 8 non-

rotatably connected to an enlarged portion 9 of the screw shaft and seating against a shoulder 11 thereon. The other end of the spring is anchored to the sleeve 1 by means of a similar anchor member 12 non-rotatably mounted on an enlarged portion 10 of the sleeve and adapted to bear against a split thrust ring 13 seated in a groove 14 in the sleeve.

Locating and retaining means for the sleeve on the motor shaft 6 is provided in the form of 10 a pin 15 slidably mounted in a radial aperture 16 (Fig. 3) in the sleeve and adapted to extend inwardly into an opening in the shaft as indicated in dotted lines in Fig. 2, being retained in such position by the anchoring member 12 when the 15 drive is mounted on the motor shaft. A key 17 (Fig. 2) of standard construction is preferably provided for non-rotatably connecting the sleeve to the motor shaft when mounted thereon.

When the drive is assembled for shipment, the 20 pin 15 is held in withdrawn position and the parts so retained thereby as to facilitate mounting on the motor shaft. As here illustrated, this is accomplished by making the opening 16 in the sleeve slightly larger than the pin 15 and by 25 forming a shallow circumferential recess or groove 18 adjacent the outer end of the pin. When the parts are assembled, the spring 7 is compressed sufficiently to permit the anchor member 12 to clear the opening 16 in the sleeve, 30 whereupon the pin 15 is inserted in said opening and the spring 7 permitted to expand. The expansion of the spring forces the anchor member 12 against the pin 15, causing it to tilt slightly 35 and bind in the opening 16 whereby it is held firmly against displacement due to handling or vibration during shipment and distribution.

The anchor members 8 and 12 are formed commercially as stampings, and when so formed, there is a sharp edge or corner 19 left around its central opening. The recess or groove 18 in the pin 15 is formed to accommodate the edge 19 on anchor member 12 (Fig. 3), forming therewith an interlocking connection which further insures against undesired dislodgment of the pin 15.

45 When the drive is to be mounted on a motor shaft, it is merely necessary to place a key 17 in the shaft and then slide the drive on the shaft until the pin 15 registers with the opening in the shaft. The pin 15 is then forced into said opening, whereupon the spring 7 expands and moves the anchor member into the position illustrated in Fig. 1 where the parts are all locked in position.

50 Although but one embodiment of the invention 55

has been shown and described in detail, it will be understood that other embodiments are possible and various changes may be made in the arrangement of the parts without departing from the 5 spirit of the invention as defined in the claims appended hereto.

What is claimed is:

1. In a starter drive, a sleeve adapted to be mounted on a motor shaft, a screw shaft slidably journalled on the sleeve, means transmitting rotation from the sleeve to the screw shaft including a torsion and compression spring and an anchor member therefor slidably but non-rotatably mounted on the sleeve, and means including 15 a pin loosely mounted in the sleeve and adapted to serve as an abutment for said anchor member to limit the expansion of the spring, said pin and anchor member having interengaging portions serving to resist displacement of the pin.
2. In an engine starter drive, a sleeve, a hollow shaft slidably journalled thereon, a stop member on the sleeve limiting sliding movement of the shaft in one direction, a drive spring, means 20

anchoring one end of the spring to the shaft, 5
slidable means non-rotatably connecting the other end of the spring to the sleeve, and a pin loosely mounted in the sleeve adapted to engage said slidable means to hold the spring under compression, the expansive force of the spring serving to bind the pin in the sleeve and resist dislodgment thereof.

3. In an engine starter drive, a sleeve, a hollow shaft slidably journalled thereon, a stop member 10 on the sleeve limiting sliding movement of the shaft in one direction, a drive spring, means anchoring one end of the spring to the shaft, 15
slidable means non-rotatably connecting the other end of the spring to the sleeve, and a pin 20 loosely mounted in the sleeve adapted to engage said slidable means to hold the spring under compression, said pin having a recess and said slid-
able means having a portion adapted to engage in said recess under the expansive force of the spring and resist dislodgment of the pin.

MAURICE P. WHITNEY.
